UNITED STATES PATENT OFFICE.

IRVING BLOUNT, OF NEW YORK, N. Y.

ASH-CHUTE.

1,055,311.

Specification of Letters Patent.

Patented Mar. 11, 1913.

Application filed July 13, 1911. Serial No. 638,290.

To all whom it may concern:

Be it known that I, IRVING BLOUNT, a citizen of the United States, and a resident of the borough of Brooklyn, city and State of New York, have invented certain new and useful Improvements in Ash-Chutes, of which the following is a specification.

This invention relates to means for conducting ashes from the ash box of a range, or other cooking or heating stove, or furnace or the like, to an ash receptacle arranged at a lower level; and it consists in the novel features hereinafter described and particularly pointed out in the subjoined claims.

One of the important purposes of the present invention is to provide a means of the kind stated, which will automatically prevent the passage of ashes from the chute when the ash receptacle is not in position to receive the same.

Another important purpose of the present invention is to provide an ash chute of the kind employing a movable hood for the ash receptacle, with means whereby the chute will be automatically closed by movement of the hood to a position in which it permits the ash receptacle to be conveniently removed for disposal of the contents of the latter.

These purposes, and others which will hereinafter fully appear, are secured by the construction illustrated in the accompanying drawings to exemplify what is now regarded to be the best detail embodiment of the invention. It is to be understood however that the invention is not restricted to the precise details illustrated in the drawings and hereinafter particularly described, as changes may be made in the details without departing from the spirit of the invention or the scope of the subjoined claims.

In the drawings, wherein like characters of reference denote corresponding parts in the several views: Figure 1 is a vertical section through a part of a stove and an ash chute embodying the present improvements. Fig. 2 is a detail elevation of the lower end of the ash chute, the hood and the ash receptacle, the hood being shown in its raised position from the receptacle.

A designates the ash box of a range, furnace or other cooking or heating device and B designates an ash chute arranged below the same and serving to conduct the ashes to an ash receptacle C located in the cellar.

for example. This receptacle C is removable from the outlet of the chute and its mouth is preferably of greater area than the outlet of the chute, as shown. Between said outlet and mouth a hood D preferably flaring to cover the receptacle C, is arranged to prevent the dissipation of the dust into the cellar or other room containing the receptacle. This hood has a flanged lower end 10 which fits over the mouth of the receptacle C and it is movably mounted on the chute B to permit it to be raised to permit the receptacle to be removed when the contents of the latter are to be disposed of. The 15 chute is provided with a damper or valve E for closing it when the receptacle is removed, and means are provided whereby this damper or valve is closed automatically when the hood D is raised from the receptacle C. In the herein exemplified form of the invention this is accomplished by securing the damper or valve E to a shaft 12 which is journaled in the opposite walls of the chute and has outside the latter an actuating arm 13 which extends into the path of the upper end of the hood, (or of a member 14 which moves with said hood and practically forms a part of the latter) whereby the raising of the hood will correspondingly raise said arm and thereby turn the damper or valve to the position in which it closes the chute. A holding element 15 of suitable construction cooperates with a lip or projection 16, or other suitable part 20 of the hood, for holding the latter in its elevated position. When the receptacle C has been emptied and restored to its operative relation with the chute the hood D is released and returns to its receptacle-closing 25 position, and the arm 13 falls and automatically opens the damper or valve E. In the exemplified form of the invention, this falling of the arm is accomplished by gravity.

The chute B is preferably provided with a flaring mouth 16^a presented to the ash box A and of area approximately equal to the area of the lower surface of the latter, and grate bars 17 are preferably employed between the mouth of the chute and said ash box to effect a preliminary separation of the ashes from the cinders etc. A slide valve 18, or other suitable manually-operable closure for said mouth, is preferably employed 30 in order that the attendant may control the delivery of the ashes to the chute. The

chute itself is also preferably provided with a means for screening or sifting the ashes in the passage of the latter therethrough. This screening or sifting means, when employed, preferably consists of a plurality of inclined screens 19 extending alternately, as shown, from opposite sides of the chute to provide a circuitous path for the ashes and a screen 20 extending entirely across the chute to an opening in the wall of the chute. This opening is provided with a suitable closure, as indicated at 21, and a suitable conductor, as the inclined board 22, leads therefrom for conducting the cinders away to a suitable point, it being of course understood that the ashes or finer particles pass through the screen 20 to the receptacle C while the cinder and larger particles are retained by said screen and are delivered thence to the conductor 22 when the closure 21 has been opened.

Having now described the invention, what I believe to be new and desire to secure by Letters Patent, is:-

25 1. The combination with an ash chute having a damper or valve, and an ash receptacle at the outlet end of the chute, of a device for closing the mouth of the receptacle, movably mounted with relation to the receptacle and chute, and means whereby the damper or valve is operated automatically when said device is moved.

30 2. The combination with an ash chute having a damper or valve, and an ash receptacle at the outlet end of the chute, of a hood movably mounted on the chute and closing the upper end of the receptacle, and an actuating device for the damper or valve, arranged to be operated by said hood.

3. The combination with an ash chute 40 having a damper or valve, and an ash receptacle at the outer end of the chute, said damper or valve having a shaft journaled in the walls of the chute and provided outside the latter with an actuating arm, of a 45 hood slidably mounted on the outlet end of the chute and adapted to cover the mouth of the receptacle, said hood having a member which engages said arm and acts thereon to close the damper or valve when the hood is 50 raised.

4. The combination with an ash chute having a damper or valve and a removable ash receptacle at the outlet end of the chute, of a hood for said receptacle, movably 55 mounted on the chute, means whereby raising of the hood from said receptacle automatically closes the damper or valve, and means for holding the hood in raised position.

5. The combination with an ash chute having a damper or valve, a sifting means above the damper or valve, a wall aperture with a closure operatively related to the sifting means, and means for conducting the 65 larger particles away from the chute, of an ash receptacle removably mounted at the outlet end of the chute, a hood for said receptacle, movably mounted on the chute, and means whereby raising of the hood automatically closes the damper or valve.

In witness whereof I have hereunto set my hand at the city, county and State of New York, this 28th day of June, 1911.

IRVING BLOUNT.

In presence of—

ISABEL R. RICHARDS,
JOHN J. RANAGAN.
